SHOE HOLDER OR STRETCHER

Fred Randolph Smith, Tacoma, Wash.

Application April 18, 1947, Serial No. 742,235

6 Claims. (Cl. 12—128.3)

1

This invention relates to devices for holding a shoe while being cleaned and polished, and has for its objects to provide a simple, inexpensive, device which may be removably mounted on a wall, post, or other vertical surface; which will firmly hold the shoe while being manipulated; which is readily adjustable to fit practically any size and shape of shoe; which will firmly support the upper surface of the shoe while it is being worked on; which is strong and rigid while holding the shoe; and which is simple in construction and to install in operable position, easy to adjust to fill out the shoe, and effectively fulfills its purpose.

I attain these and other objects by the devices, mechanisms and arrangements illustrated in the accompanying drawings, in which—

Fig. 1 is a plan view of my improved shoe holder, showing it as being inserted into a shoe and, in broken lines, showing it expanded to fill the shoe; Fig. 2 is an isometric view thereof; Fig. 3 is a rear elevation of the supporting plate by which it is secured to the wall; Fig. 4 is a section thereof, taken on the line 4—4 in Fig. 3 and showing a portion of the movable bracket extending therefrom; Fig. 5 is a section thereof, taken on the line 5—5 in Fig. 3; Fig. 6 is an enlarged view of the upper ends of the brackets disassociated from the supporting plate; and Fig. 7 is a side elevation of the rack for holding the brackets in adjusted expanded position.

Similar numerals of reference refer to the same parts throughout the several views.

Though many devices have been developed for holding a shoe while being cleaned and polished I find that they are generally too complicated to make to permit them to be marketed at a reasonable price, or they are too flimsy to be strong and firm when in use; also the means for expanding them to fill out the shoe is generally dependent on a central expansion of the toe pieces, thus failing to fill out the toe portion of the shoe in true conformity to the shape of the shoe; they also generally require too much manipulation of the expanding mechanism to be simple, quick and easy to adjust.

In order to improve these conditions I have provided a shoe holder which is simple, strong and firm when in use, which will fit any length of shoe, and which automatically fits any shape of toe.

Referring to the drawing, the securing plate 10 is provided with an elongated slot 11 at its upper end, and two slots 12 in its lower edge, said openings being adapted to permit the plate 10 to

2

be slipped under the heads of three screws previously inserted in the vertical wall or post, whereby the plate and the shoe holder may be firmly held in place while in use, and from which it may be readily removed when not in use. The rear side of the plate 10 is appropriately dished to provide room for the securing tongues, hereinafter described, and to bring the rim of the plate flat against the wall.

10 On the left side of the dished plate 10 (as viewed in Fig. 3) are two vertical slots 13 and a single horizontal slot 14. These slots are adapted to receive the tongues 15, formed on the end of the fixed bracket 16. The tongues 15 are clinched tightly against the rear side of the plate 10 to hold said bracket 16 fixedly in position. The right side of said plate 10 is provided with three vertical slots 17, similar to the slots 13. These slots 17 are adapted to receive the tongues 18 of

15 the movable bracket 19. These slots and tongues are in vertical alinement and the tongues are bent in opposite directions in the rear of the plate 10 but are not clinched tightly thereagainst, thus holding the bracket 19 in firm, vertical position but allowing it a slight lateral movement in relation to the fixed bracket 16 (Fig. 5).

20 The two brackets 16 and 19 are each composed of a vertical part 20 and an out-turned horizontal part 21 forming a very stiff and strong "angle iron" shape.

25 The fixed bracket 16 is provided with a rack-bar 22 loosely pinned to it (Fig. 1) and passing through a hole in its vertical side 20. This bar 22 passes across the space between the brackets 16 and 19 and through a hole 23 in the vertical side of the bracket 19. The bar 22 is provided with rack teeth 24 in its lower edge, said teeth being adapted to engage the lower edge of the said hole 23 to hold the said bracket 19 in adjusted lateral position, as hereinafter described. A knob 25 may be provided at the end of the bar 22 to facilitate its being freed from engagement with the bar 19.

30 The two brackets 16 and 19 extend downward in parallel inclines to the lower end thereof. A pair of complementary toe pieces 26 are pivoted to the ends of the respective brackets 16 and 19 in such manner that they are perfectly free to swing on their pivots, independent of each other, to fill and to fit the inside of the shoe, whether the shoe be small or large, for the right foot or the left foot, when the shoe is thrust thereover. It will be particularly noted that the two toe pieces 26 are wholly disconnected from each other and can therefore assume any positions on the

brackets to fill and fit the inside of the shoe, and that they extend a sufficient distance to support the upper surface of the shoe to brace it while being cleaned or polished.

The bracket 19 is provided with a series of rack teeth 27 on its lower edge. A heel holder 28 is mounted on the said bracket 19. This heel holder comprises a bent metal member, having a slot 29 at its upper end, said slot spanning the horizontal member 21 of the said bracket 19. The holder 28 arches at 30 over the said horizontal member 21 and is provided with a central slot 31 through which the said bracket 19 passes. The lower edge of the said slot 31 is adapted to engage one of the rack teeth 24 on the lower edge of the member 20 of the said bracket. The lower part 32, of the heel holder 28 is adapted to engage the inside of the heel of the shoe.

The heel holder, therefore, may be freely slid up the bracket 19 until the part 32 engages the heel of the shoe, when further pressure on the arch 30 causes the holder 28 to raise slightly, bringing the lower edge of the slot 31 into engagement with the teeth 27 and causing a slight distortion of the arch 30, which therefore acts as a spring, thus insuring the firm hold of the part 32 on the shoe heel.

When the shoe is placed on my improved shoe holder, and is pressed as far thereon as possible, the bracket 19 is pressed away from the bracket 16, thus spreading the ends of the two brackets apart so that the toe pieces 26 completely fill out the toe portion of the shoe, then the heel holder 28 is pushed as far up on the bracket 19 as it will go until the part 32 tightly holds the heel of the shoe under the tautened spring action of the arch 30. To release the shoe from the holder it is necessary to release the bracket 19 from the rack bar 22 and the heel holder from the rack teeth 27.

It is, of course, understood that many changes may be made in the details of my improved shoe holder without departing from the spirit of my invention as outlined in the appended claims.

Having, therefore, described my invention, what I claim and desire to secure by Letters Patent is:

1. In a shoe holder the combination of a wall plate; a fixed bracket secured thereto and extending out therefrom; a movable bracket secured thereto and extending out therefrom and having a slight lateral motion in relation to said fixed bracket; means mounted on one said bracket and engaging the other said bracket to hold them in selected position relative to each other; and toe pieces pivotally mounted on the ends of said brackets, whereby said toe pieces may swing to fill the shoe toe when said laterally movable bracket is swung away from said fixed bracket.

2. In a shoe holder, the combination of a wall plate; a fixed bracket secured thereto and extending out therefrom in downward incline; a

movable bracket secured to said wall plate and extending therefrom in parallel incline to said fixed bracket and having a slight lateral motion in relation to said fixed bracket; ratchet means

5 mounted on said fixed bracket and engaging said movable bracket to hold it in selected position relative to said fixed bracket; and toe pieces pivotally mounted on the ends of said brackets, whereby said toe pieces may be swung to fill the shoe toe when said laterally movable bracket is swung away from said fixed bracket.

10 3. In a shoe holder as set forth in claim 2, wherein said toe pieces are wholly independent each of the other.

15 4. In a shoe holder as set forth in claim 2, together with a heel holder, slidably mounted on said movable bracket and adapted to engage and hold the heel of the shoe; and means to maintain said heel holder in selected position on said bracket.

20 5. In a shoe holder, the combination of a wall plate; a fixed bracket secured thereto and extending out therefrom in downward inclined position; a second bracket secured to said wall plate 25 and lying parallel with said first bracket and having a slight lateral movement in relation thereto; ratchet means mounted on the first bracket and engaging the second bracket to hold it in selected position relatively to the first bracket; toe pieces pivotally mounted on the ends of said two brackets; a heel holder slidably mounted on said second bracket; and means to hold the heel holder in selected position on said second bracket.

30 35 6. A shoe holder as set forth in claim 5, wherein said heel holder comprises a resilient body, and wherein said means to hold the heel holder in selected position comprises a rack formed on said second bracket and engaged by said heel holder, the resilient portion thereof being distorted by the pressure between the shoe heel and the heel holder, to firmly hold the heel holder in adjusted position.

45 FRED RANDOLPH SMITH.
